CARBURETOR

Hareld H. Timian, Detroit, Mich., assignor to
Continental Motors Corporation, Detroit, Mich.,
a corporation of Virginia

Application November 12, 1932, Serial No. 642,353

6 Claims. (Cl. 261—52)

My invention relates to carburetors and more particularly to means for controlling the throttle valve and mixture of a carburetor associated with a hydrocarbon motor.

Heretofore it has been customary to provide a single control for the throttle valve of the engine and a separate control for the choke valve of the carburetor most generally employed to facilitate starting of the engine. Because the throttle valve is usually adjusted for idling operation of the engine, it is customary to provide an additional throttle valve control (usually a hand device) which can be actuated when desired to partially open the carburetor throttle valve to facilitate engine starting or road speed settings.

It has been proposed to provide means for interconnecting the throttle and choke valves of a carburetor so as to progressively open the throttle valve as the choke valve is closed, but with such devices, it is found that in most cases the throttle valve is opened an excessive amount when the choke valve is fully closed resulting in waste of fuel and racing of the engine on starting. The speeding up of an engine after starting is usually desirable so as to more quickly obtain a uniform distribution of the fuel mixture and more particularly it is desirable to quickly sweep out wet fuel accumulations in the manifold after starting the engine to obtain the desired efficient engine performance. The speeding up of the engine subsequent to engine starting will effect this result but with engines of the aforesaid type it is necessary to open the choke valve by means of one control device and to adjust the throttle valve by means of a second control. It will thus be noted that efficient engine performance on starting is largely dependent on the skill of the operator and excessive amounts of fuel are usually consumed in starting the engine as a result of carburetor flooding by improper or inaccurate manipulation of the above controls. In addition such improper manipulation of the controls often result in engine stalling due to carburetor flooding.

It is desirable to open the throttle relative to the idling position to facilitate engine starting and then to open the throttle further subsequent to starting the engine on opening the choke valve. Racing of the engine at the start is undesirable and with the constructions as heretofore used that employ separate controls for a throttle and choke valve, which are manually controlled and dependent on the skill of the operator, operation

of the engine under destructive conditions usually results.

By employing a carburetor with interconnected throttle and choke valves, engine starting is materially facilitated due to the fact that the throttle valve is opened as the choke valve is closed. However, many difficulties have arisen in connection with carburetors of the aforesaid type. The connections between the throttle and choke valves result in an operation in which the throttle valve is progressively closed on opening the choke valve subsequent to starting of the engine, and consequently the engine is frequently killed because of insufficient throttle valve opening which does not permit the supplying of a sufficient amount of fuel mixture to the engine. It becomes necessary to quickly open the throttle valve by means of the foot accelerator pedal which operation generally results in racing of the engine, waste of fuel, crankcase dilution and operation of the engine under destructive conditions.

An object of my present invention is to improve engine performance by providing a control for the throttle valve and mixture of the carburetor whereby engine starting is facilitated and the engine performance is improved without the difficulties heretofore encountered.

Another object of my invention resides in facilitating engine starting and in generally improving engine performance by providing a carburetor and associated throttle and choke valve controlling means whereby to successively adjust the carburetor and choke valve and in particular to effect a closing of the throttle valve in the direction of its idling position on closing the choke valve and vice-versa to effect a partial opening of said throttle valve on opening the choke valve for sweeping out wet fuel accumulations in the manifold subsequent to engine starting with a minimum of fuel consumption.

Other features of my present invention relate to a carburetor and the improved means for operatively connecting the throttle valve and choke valve to a single hand device whereby to control the aforesaid valve adjustments, and further I contemplate the construction of a hand device control and associated valve actuating connections whereby a relatively rapid actuation of the choke valve is obtained by employing a motion multiplying device in conjunction with the connections between the hand device and the choke valve.

A further object of my invention is to construct an improved compact controlling means for the throttle valve and choke valve of a carburetor

by providing a single hand device operable to adjust said valves and arranged solely to adjust the throttle valve during the first part of its movement and to adjust both the throttle and choke valves during the latter part of its movement.

For a more detailed understanding of my invention, reference may be had to the accompanying drawings which illustrate preferred embodiments which my invention may assume, and in 10 which:

Fig. 1 is a side elevational view of an engine and a portion of the associated vehicle illustrating the means for controlling the engine carburetor.

Fig. 2 is an enlarged side elevational view of the carburetor illustrating a means for controlling the operation of the carburetor throttle and choke valves.

Fig. 3 is an end elevational view of the carburetor shown in Fig. 2 as seen from the right of Fig. 2.

Fig. 4 is an enlarged detail view of the interconnected valve operating devices showing the throttle valve in idling position and the choke 25 valve open.

Fig. 5 is a similar detail view showing the throttle valve opened by means of the foot accelerator pedal.

Fig. 6 is a similar detail view showing the throttle valve opened by the hand device and illustrating the parts relatively positioned for the beginning of the choke valve operation.

Fig. 7 is a similar detail view showing the choke valve closed and the throttle valve partially closed 30 towards idling position for starting the motor,

Fig. 8 is an enlarged detail view of the carburetor connections incorporated with a modified form of construction giving a relatively rapid choke valve operation by employment of modified motion multiplying devices intermediate the actuating element and choke valve, the throttle 40 valve being adjusted in idling position.

Fig. 9 is an enlarged detail view of the modified showing of Fig. 8 and illustrating the independent operation of the throttle valve by means of the foot accelerating pedal,

Fig. 10 is a similar detail view showing the operation of the throttle valve by means of the hand device,

Fig. 11 is a similar detail view showing the choke valve closed and the throttle valve adjusted for engine starting.

Fig. 12 is an enlarged detail view of a further modified construction, this view showing the choke valve open and the throttle valve adjusted in idling position.

Fig. 13 is a detail view of said further modified construction illustrating the independent actuation of the throttle valve by means of the foot accelerator pedal,

Fig. 14 is a detail view showing the operation of the throttle valve by means of the hand device, and

Fig. 15 is a further detail view showing the choke valve closed and the throttle valve adjusted for engine starting.

In general, my improvement is adapted for assembly with a carburetor A associated with an internal combustion engine B, the latter being mounted for operation in the usual manner with a vehicle C, the engine being supported by the chassis D in any suitable manner. The engine herein illustrated is constructed in the usual manner and comprises in general an engine block 10 and with the usual intake and exhaust manifolds

11 and 12 respectively, said intake manifold including the usual primary fuel mixture conducting portion 13 adapted for connection with the fuel mixture outlet of carburetor A.

The carburetor A is provided with the usual adjustable throttle valve 14 for controlling the fuel mixture flow from the carburetor to the intake manifold, and the usual adjustable choke valve 15 for controlling the supply of air to the carburetor.

My present improvement relates more particularly to means for controlling the aforesaid carburetor throttle and choke valves 14 and 15 respectively, my improvement providing interconnected valve actuating devices operable from a single hand device or pull button 16, the latter being connected to an actuating element 18 by means of a "Bowden" wire 17, said element being connected with the throttle valve and choke valve of the carburetor whereby adjustment of said valves can be readily obtained as will be herein-after explained.

One embodiment of my invention is shown in Figs. 1 to 7 inclusive. It will be noted that the throttle valve 14 is carried by a shaft 19 and the choke valve 15 is carried by the shaft 20. The throttle valve is urged to a closed position by means of a suitable spring or other yielding device 21 and the choke valve is urged to an open position by a spring or other yielding device 22. A throttle lever 23 is mounted on the shaft 19 and is adapted to be actuated for adjusting the throttle valve 14. This throttle lever 23 may be actuated by means of a foot pedal 24 and suitable connections consisting of a bell crank 25 and a pull rod or Bowden wire 26 which is connected with the free end of the lever 23. In Fig. 4 the valves are adjusted and in particular the throttle valve for idling operation of the engine and the engine speed is controlled preferably during normal running operation by means of the foot pedal 24, which when actuated moves the throttle lever 23 into the position shown in Fig. 5. Fig. 5 of course shows the throttle wide open and it may be readily understood that the normal control of engine operation may be varied by adjusting the positions of the throttle valve as desired.

The actuating element 18 is preferably mounted for free rotation on the choke valve shaft 20, and in the construction shown, this actuating element is provided with an ear or arm 18' to which may be connected with a link 27, this link extending in the direction of the throttle valve and having an enlarged portion 28 adjacent its upper end which is provided with an arcuate slot 29. The throttle lever 23 is provided with an arm 30 carrying a pin 31 which is adapted to engage in the slot 29. It will be noted that when the throttle valve is operated by means of the foot pedal that the pin 31 will freely move in the arcuate slot 29 without affecting any movement of the lever 27. However, when the hand device is operated for actuating the actuating element 18 these links 27 are moved and by reason of the pin connection 31 with the throttle lever the throttle lever is then caused to be moved. It will be noted that the movement of the actuating element 18 from the position shown in Fig. 4 to that shown in Fig. 6 will cause the link 27 to move downwardly and thus partially open the throttle valve 14. Further movement of the actuating element 18 from the position shown in Fig. 6 to that shown in Fig. 7 causes a movement upwardly of the link 27 and causes the 75

throttle valve to move towards its idling position (Fig. 4). The aforesaid movement to link 27 is caused by reason of the fact that the connection of link 27 with arm 18' moves on an arc and when the same is in the position shown in Fig. 6 it is at the bottom of the arc and therefore further movement causes the arm to move upwardly on the arc carrying with it the link. Thus the first part of the movement of the hand device provides for an adjustment of the throttle valve independently of the choke valve. The position of the throttle valve shown in Fig. 7 is that which is most suitable for starting the engine.

15 The operation of the choke valve is carried out during the latter portion of the movement or actuation of the hand device 16. A lever or member 32 is fixed to the shaft 20 which carries the choke valve, and the outer end of this member 20 carries a pin 33 which operates in a slot 34 of a link 35, this link being connected to the link 27 by a pivot joint 36. The slot 34 permits relative movement of the link 35 and the arm 32 carried by the choke valve shaft 20, and this link 35 is positioned so as to be engaged by an ear or other suitable protection 36 carried by the actuating element 18. The construction of these elements is such as to not engage the projection 36 with link 35 until the throttle valve has been 25 opened to its widest position by means of link 27. Further movement of the actuating element 18 which as aforesaid causes the throttle valve to be moved towards its idling position, effects a moving of the choke valve lever 32 as the projection 36 engages link 35 and moves the same into the position as shown in Fig. 7. It will be noted in Fig. 7 that the choke valve is completely closed, the choke valve moving through an arc of approximately 75° but the actuating element 18 is moved through an arc less than 75° because of the motion multiplying device forming the connection between the choke valve and actuating element. This motion multiplying means between the actuating element 18 and choke valve may be readily seen in comparing Figures 6 and 7 which show the beginning of the choke valve movement and the ending of the choke valve movement respectively. It will be noted that the lever 32 attached to the choke valve moves or rotates at a greater relative speed than the angular movement of the actuating element 18. The closing movement of the choke valve is had while moving the throttle valve towards its idling position, and the adjustment of the throttle valve when the choke valve is closed is such as to permit ready starting of the engine.

60 It will be noted that the throttle valve lever 23 is positively connected to the throttle valve and may be actuated by means of the foot accelerator independently of the choke valve operation, and by means of the hand device whenever desired by reason of the aforesaid connections which connect the throttle valve with the actuating element 18.

65 In the construction illustrated in Figs. 8 to 11 inclusive, I have shown a modified construction in which a lesser number of parts are employed and which is relatively simpler and more compact in construction. In this modified construction I have provided a motion multiplying device between and intermediate the actuating element and choke valve in which the choke valve is actuated by reason of a shortened lever arm whereas in the construction illustrated in Figs. 1 to 7 in-

clusive a toggle arm construction is employed for effecting said multiplication of motion.

This modified construction employs a throttle arm lever 23 to which the foot accelerator pedal is connected in the usual way, said lever having an arm 30 carrying a pin 31 adapted for sliding engagement in an arcuate slot 29' of a link 27'. In the actuation of the throttle lever 23 by said foot pedal the pin is free to move in the arcuate slot 29' without actuating the link 27', but movement of the link 27' will actuate the lever 23 and effect an adjustment of the throttle valve 14.

15 The operation of this modified structure effects substantially the same results as the operation of the structure illustrated by Figs. 1 to 7 inclusive. An actuating element 40 rotatively mounted on the choke valve shaft 20 is employed, this element having an arm 40' to which the other end of link 27' is pivotally connected as at 41. Actuation of said element 40 from the position shown in Fig. 8 to that shown in Fig. 10 effects an adjustment of the throttle valve 14 without moving the choke valve as the link 27' is moved downwardly, but further movement of the element 40 engages the edge of link 27' with a pin 42 or other suitable projection carried by a member 43 fixed or otherwise secured to the choke valve shaft 20 and thus an actuation of the choke valve is obtained. The continued movement of the actuating element 40 raises the link 27' and thus moves the throttle valve towards the idling position while at the same time closing the choke valve by reason of the engagement of the link 27' with pin 42 of member 43.

35 It will be noted that the lever arm for actuating the choke valve (the distance from pin 42 to the axis of the choke valve shaft) is less than the lever arm for actuating the throttle valve shaft (the distance between pivot 41 and the axis of the choke valve shaft). Thus the linear movement of the link 27' induced by a definite angular movement of arm 40' from Fig. 10 to Fig. 11 position, causes substantially the same linear movement of pin 42 but because of the fact that pin 42 carried by member 43 moves on a shorter 40 radius, i. e., it has a shorter lever arm, the member 43 fixed to the choke valve shaft is moved through a greater angle and thus effects a complete closing of the choke valve (Fig. 11) while the throttle valve has been only part way returned towards its idling position. The position of the carburetor valves shown on Fig. 11 may be termed the starting position, it being that position of the valves most desirable for starting the engine.

45 The actuating element is connected with the hand device 16 by means of a "Bowden" wire 17 in a manner similar to the connection shown in connection with Figs. 1 to 7 inclusive. The springs associated with the throttle and choke valve shafts respectively urge the same to a closed and open position. The members 32 and 43 are respectively provided with arms 32' and 43' adapted for engagement with a suitable abutment 44 carried by the carburetor casing whereby to 50 limit the choke valve movement.

55 Figs. 12 to 15 illustrate a further modified form of construction in which movement of the hand device 16 in one continuous direction first effects an adjustment of the throttle valve and then an adjustment of the choke valve while at the same time reversing the movement of the throttle valve.

70 The throttle valve 14 is secured to shaft 19 and a throttle lever 50 is fixed or otherwise keyed to 75

this shaft. The lever 50 is connected with a foot accelerator pedal 24 by means of a bell crank or lever 25 and "Bowden" wire 26. The lever 50 is provided with an arm 51 carrying a pin 52 adapted for engagement in an arcuate slot 53 carried by the link 54. Thus, the throttle valve may be moved in any desired adjusted position by means of the foot pedal without moving link 54 by reason of the slotted connection between 10 the pin 52 and link 54 (see Fig. 13).

Adjustment of the throttle and choke valve is had by means of the hand device actuation and associated connections. An actuating element 55 is connected with the hand device 16 by means 15 of the "Bowden" wire 17 and is rotatably mounted on the shaft 20 to which is secured the choke valve 15. The element 55 is provided with one arm 56 to which the link 54 is pivotally connected as at 57 and another arm 58 carrying a 20 projecting lug or other suitable means 59 which is adapted for engagement with a member 60 fixed or otherwise keyed to the shaft 20. Said member 60 is provided with a lug or other projection 61 adapted for engagement with a stop 25 or abutment 62 for limiting the closing movement of the choke valve.

The first part of the hand device operation moves said actuating element 55 from Fig. 12 position to Fig. 14 position and by reason of the 30 link 54 connecting the arm 56 to the arm 51 of the throttle lever, the throttle valve 14 is thereby adjusted. During this initial adjustment of the throttle valve, no movement is imparted to the choke valve 15, but further movement of the 35 hand device in the same direction moves the actuating element from Fig. 14 position to Fig. 15 position, and the choke valve is moved to a closed position by reason of the engagement of projection 59 with the member 60. Simultaneous 40 with the closing movement of the choke valve 15 the throttle valve is also moved towards its idling position but the upward movement of link 54 in moving from Fig. 14 position to Fig. 15 position only moves said throttle valve part way towards 45 the idling position.

The above described operation is made possible in the present instance by reason of the different lengths of lever arms, arm 51 being relatively longer than arm 56 so that the linear travel of link 54 by reason of the angular movement of member 60 results in a relatively less angular movement of arm 51 to which the upper end of link 54 is attached.

In all three structures illustrated in the accompanying drawings, it will be noted that I have provided for operation of the throttle and choke valves of the carburetor by means of a single hand device, and can obtain an adjustment of the throttle valve independently of the choke valve operation during the first part of hand device actuation while during the latter part of said hand device actuation an adjustment of said choke valve is obtained. Incidentally a partial closing of the throttle valve is obtained when closing the choke valve by means of the hand device, and on opening the choke valve after starting the engine the throttle valve is opened somewhat prior to finally moving same to its idling position thereby effecting more efficient engine operation and eliminating the tendency towards destructive engine operation due to unskillful actuation of the carburetor controls heretofore employed.

It will be apparent to those skilled in the art to which my invention pertains that various

modifications and changes may be made therein without departing from the spirit of my invention or from the scope of the appended claims.

What I claim as my invention is:

1. In a carburetor provided with a throttle valve, actuating means positively connected to the valve for operating the latter, means for operating said valve and including a hand device and an actuating element, the latter operatively connected with said actuating means to open 10 said valve from an idling position and then to move same towards its idling position on movement of said hand device in the same direction, and a choke valve structure for the carburetor, including a shaft, a valve element and a lever secured to the shaft, said actuating element rotatably supported on said shaft and engageable with said lever to adjust the choke valve.

2. In a carburetor having a throttle valve and a choke valve, throttle valve adjusting means, control means for said valves including a hand device and an actuating element operated by said hand device independently of said throttle valve adjusting means, actuating means connected with said element and operatively connected with 20 the throttle valve for adjusting same on operating said hand device, said actuating means having a connection with said throttle valve permitting the adjustment of said throttle valve independently of said hand device operation, and means operatively connecting said element with the choke valve and including motion multiplying devices operable only during the latter portion of the hand device operation for adjusting 30 the choke valve.

3. In a carburetor provided with a throttle valve, means positively connected to the valve for operating the latter and including a throttle lever and a link, means connecting said link and lever permitting actuation of the lever independently of said link, a choke valve for said carburetor, and other valve operating means including a hand device and an actuating element positively connected with the hand device and with said link, means including a lost motion connection for connecting the actuating element with the choke valve, said throttle valve being adjusted during the first part of the hand device operation, the latter part of said hand device operation engaging said element with the choke valve to adjust same 40 subsequently to the initial adjustment of the throttle valve.

4. In a carburetor provided with a throttle valve, means positively connected to the valve for operating the latter and including a throttle lever and a link connected to said lever, a choke valve for said carburetor, and other valve operating means including a hand device and an actuating element positively connected with the hand device, said actuating element connected 60 with said throttle valve operating means whereby to solely adjust said throttle valve during the first part of the hand device operation, the latter part of said hand device operation engaging said element with the choke valve to adjust same 65 while simultaneously effecting a further actuation of the throttle lever and link whereby to further adjust said throttle valve.

5. In a carburetor provided with a throttle valve, means positively connected to the valve 70 for operating the latter, a choke valve for said carburetor, and other valve operating means including a hand device and an actuating element positively connected with the hand device, said actuating element connected with said throttle 75

valve operating means whereby to solely adjust said throttle valve during the first part of the hand device operation, motion multiplying means connecting said element with the choke valve, the latter part of said hand device operation actuating said last mentioned means whereby to move the choke valve to close same and actuating the connections intermediate the element and throttle valve to also move said throttle valve towards its idling position.

6. In a carburetor provided with a throttle valve, means positively connected to the valve for operating the latter, a choke valve for said carburetor, and other valve operating means in-

cluding a hand device and an actuating element positively connected with the hand device, said actuating element connected with said throttle valve operating means whereby to solely adjust said throttle valve during the first part of the hand device operation, means operatively connecting said element with the choke valve to close same during the latter part of said hand device operation and including motion multiplying means, said connections between the element and throttle valve being further actuated to move said throttle valve part way towards its idling position on closing said choke valve.

HAROLD H. TIMIAN.
